UNITED STATES PATENT OFFICE

2,268,068

OIL BURNER

Le Roy F. Deming, Kansas City, Mo.

Application December 5, 1938, Serial No. 244,104

7 Claims. (Cl. 158—91)

This invention relates to oil burners for stoves, furnaces and other heating devices, wherein is provided a fire box and combustion chamber, and the primary object is to provide an oil burner having a specially formed preheater through which is fed the supply of air supporting combustion and wherein is disposed one end of an oil supply duct that terminates in a conductor of a special nature, to the end that the oil introduced is kept below a predetermined or adjusted temperature and so that vaporization might not occur until immediately before combustion.

A yet further aim of this invention is the provision of an oil burner having a preheater, a baffle therein and means associated with said preheater and baffle for introducing oil to a point immediately adjacent to the zone of combustion without imparting heat thereto, to the end that carbonization is reduced to a point where it will not harmfully effect operation and the efficiency of the burner is raised.

Another important object of this invention is to provide an oil burner for cook stoves, heating stoves and furnaces that may be installed without greatly altering the construction of the fire boxes or combustion chambers thereof, and which will operate after installation, in an efficient manner which will insure operation without interference from carbon even when using crude oil.

A still further object of the invention is the provision of an oil burner of the aforementioned character wherein is included a specially formed preheater having a baffle therein which acts upon the air supporting combustion in such fashion as to direct it through paths of travel best suited for the contemplated heat transfer.

A large number of minor objects of the invention will appear during the course of the following specification, referring to the accompanying drawing wherein:

Figure 1 is a vertical central section through a portion of a furnace having an oil burner installed in the combustion chamber thereof, which burner is made to embody the present invention.

Fig. 2 is a horizontal sectional view taken on line II—II of Fig. 1.

Fig. 3 is an enlarged fragmentary detailed vertical sectional view through a portion of the pan and plate assembly.

Fig. 4 is a detailed elevational view of a conductor embodying a modified form of the invention; and,

Fig. 5 is a detailed elevational view of still an-

other form of conductor which extends between the oil supply tube and the underlying pan.

Designers of oil burners have heretofore been particularly concerned with the problem of creating an oil burner which would operate without the formation of carbon to the extent of causing interference with its operation. This problem has been connected with the necessity and desire to use a low grade hydrocarbon that would vaporize sufficiently to maintain a constant flame in the zone of combustion.

One of the most difficult factors in creating oil burners that would burn a cheap grade of oil and yet operate efficiently without harmful formation of carbon, was to maintain the column of oil being fed to the burner at a temperature where vaporization could not occur until immediately prior to flashing.

The combination of parts shown in the accompanying drawing, has been found to be satisfactory and therefore, the illustrated embodiment is the preferred form which will be described.

The ordinary furnace 8 having a shell 10 within its outer jacket 12 is usually supplied with a door 14, which may be utilized when installing the burner. A passageway 16 connects the conventional stack so that gases and other objectionable products of combustion may escape.

In place of the grate, which is usually at the bottom of the combustion chamber 18 of furnace 8, it is desirable to install a solid plate 20 that carries pan 22, having upwardly extending continuous side flange 24 so that the oil may be held therein when the burner is generated, or in the event oil should reach the burner without the possibility of burning.

Pan 22 has an apertured boss 26 at the center thereof which is internally threaded, as shown in Fig. 3.

A frusto-conical plate 28 is mounted upon boss 26 at the center of pan 22 so that any oil reaching the upper face thereof, will be directed into the pan. This plate 28 is provided with a center internally threaded bore 30 into which is projected nipple 32 which is externally threaded so that it enters the openings in the pan and plate as shown in the detail.

A downwardly directed, externally threaded pipe section 34 depends below pan 22 and is provided with a cap 36 against which may rest one end of conductor 38 when the type shown in Figs. 1 and 3 is employed. This conductor 38 is in the nature of a smooth rod having threads 40 thereon along a portion of its length. Spacing

nuts 42, threaded onto conductor 38, have an external contour similar to the internal contour of nipple 32 and pipe section 34, so that conductor 38 is held in a vertical position when the parts are in the assembled relation.

The hollow preheater 44 is composed of a lower casting 46 and an upper casting 48, the former being provided with an outlet port 50, while the latter has an inlet port 52 in the upper wall thereof. These ports 50 and 52 are in opposed relation when castings 46 and 48 are together, as shown in Fig. 1. Lower casting 46 has a plurality of fins 54, each of which has a portion thereof exteriorly thereof of the preheater 44 and a portion on the inner side thereof. The portions of fins 54 inside of lower casting 46 are made to support baffle member 58 which has a hollow tubular, elongated boss 58 extending to each side thereof at its axis. This boss 58 receives one end of oil supply tube 60 and the boss is long enough to circumscribe a portion of tube 60 near the end thereof and a substantial portion of the length of conductor 38 near the end which is projected into tube 60.

The internal diameter of boss 58 should be sufficient to permit a small amount of air to pass downwardly between the inner face thereof and the outer faces of tube 60 and conductor 38. Inlet port 52 is in communication with an air supply duct 62 that extends to a point outside the furnace shell 10. Air is fed to supply duct 62 through any suitable connecting pipe 63 that may receive air from a blower, not here shown, or which may terminate at any point exteriorly of the furnace, merely for the purpose of admitting air to duct 62.

It is notable that pipe 60 extends along duct 62 in spaced relation to the side walls thereof and when air is passing to the burner to support combustion, it impinges and sweeps along the outer face of tube 60 to maintain the oil therein at a temperature below that permitting vaporization. Tube 60 is connected to any suitable source of oil supply through the medium of a pipe 66 and the conventional control valve 68 may be used if desired.

A pilot light is provided at the end of pipe 70 and gas is to be used to maintain this pilot light in an operative condition, all as is known in the art.

An overflow pipe 72 extends outwardly from within furnace 8 from a point within pan 22 so that if the burner should be extinguished for any undesirable reason, the collecting oil will be drained from pan 22. If desired, the oil escaping through pipe 72 may be used to automatically cut off the supply of oil through tube 60, in a well-known manner.

The oil entering the burner through pipe 60 is conveyed along the outer surface of conductor 38 and since it is important to keep the oil within tube 60 as cool as possible, the formation of conductor 38 may be altered to further insure that heat will not be transferred through conductor 38.

Figs. 4 and 5 illustrate different ways of constructing the conductor which has before been indicated by the numeral 38.

In Fig. 4 the conductor 80 is in the nature of an ordinary rod around which has been spirally wound a wire 82, which directs the flow of oil in a downward spiral path until vaporization occurs.

The conductor 90, illustrated in Fig. 5, is of a different type in that an ordinary link chain 75

has been employed, and when oil escapes from the end of tube 60, it will flow downwardly by gravity over the outer surface of the links of chain 90, to a point where vaporization occurs.

5 The links of chain 90 have a limited amount of their surfaces in direct contact and therefore, heat exchange is discouraged, especially since air is passing around the links to further break up a direct path of travel for heat units.

10 In the operation of the oil burner, it is obvious that fuel oil is fed through tube 60 and that as it is being directed to the inner end of tube 60, a cooling effect is had thereon because of the relation of tube 60 and duct 62. As the 15 air approaches the zone of combustion, above plate 28, it is quickly heated by contacting the inner faces of the parts which form preheater 44. It also contacts the inner faces of fins 54 and by the time it passes through outlet port 50, 20 it is sufficiently heated to act upon the oil and maintain combustion, whereupon a flame is created to be directed outwardly around the faces of fins 54 and along the outer face of preheater 44. The direction of travel of the air is indicated by the arrows, shown in Fig. 1, and the 25 nature of plate 28 is such that if oil should reach the top thereof without becoming vaporized, it will burn and if a carbon deposit is formed, it will not be excessive and will not interfere with the proper functioning of the burner.

The upper face of plate 28 is constantly swept by the incoming air and the zone of combustion is defined by the edge of lower casting 46, which 30 forms outlet port 50 and plate 28.

The principles embodied in the oil burner illustrated herewith and above described, may be built into burners having different physical characteristics than that embodying the preferred 40 form, and it is obvious to one skilled in the art that smaller oil burners made in a different manner, may be constructed for use in smaller heating stoves, cooking ranges, and domestic cook stoves.

45 Having thus described the invention, what is claimed as new and desired to be secured by Letters Patent is:

1. In an oil burner of the character described, 50 a pan adapted to be positioned in the fire box of a stove or the like; a hollow air preheater above the pan, provided with an outlet port in the bottom thereof above said pan and an inlet port in the top thereof; an air supply duct in communication with the inlet port of the preheater extending to a point exteriorly of the fire box; an oil supply tube within the air duct having one end within the preheater above the outlet port and spaced above said pan; a conductor for the oil bridging the space between the oil supply tube and said pan, said conductor being formed to receive oil from the oil supply tube and convey the oil toward the pan along the outer surface thereof; a baffle within the preheater; and a plurality of fins integral with the preheater, said fins having portions thereof within the preheater adapted to operably carry the baffle in spaced relation with the inner face of the preheater, the lower wall of said preheater, said baffle and the said portions of the fins in the preheater combining to create a number of radially disposed passages around the conductor.

2. In an oil burner of the character described, 55 a pan adapted to be positioned in the fire box of a stove or the like; a hollow air preheater above the pan, provided with an outlet port in

the bottom thereof above said pan and an inlet port in the top thereof; an air supply duct in communication with the inlet port of the preheater extending to a point exteriorly of the fire box; an oil supply tube within the air duct having one end within the preheater above the outlet port and spaced above said pan; a conductor for the oil bridging the space between the oil supply tube and said pan, said conductor being formed to receive oil from the oil supply tube and convey the oil toward the pan along the outer surface thereof; a baffle within the preheater; and a plurality of fins integral with the preheater, said fins having portions thereof within the preheater adapted to operably carry the baffle in spaced relation with the inner face of the preheater, said fins, the bottom of said preheater and the baffle cooperating to divide the air entering said preheater into a plurality of paths converging as the said conductor is approached.

3. In an oil burner of the character described a hollow preheater adapted to be positioned in a fire box of a stove or the like and provided with an outlet port in the bottom thereof and an inlet port in the top; means for supplying liquid fuel to the burner having one end within the preheater above the outlet port; means for delivering air to the inlet port from outside the fire box; a baffle within the preheater formed to cooperate with the walls of the preheater in directing air from the inlet port to the outlet port through a circuitous path whereby to heat the air; a conductor depending below the end of said liquid fuel supply means and adapted to convey the liquid fuel toward the zone of combustion and the outlet port of the preheater; a tubular boss circumscribing the said conductor and positioned to direct a portion of the air from outside the fire box, downward along the conductor to maintain the temperature of the liquid fuel below the flash point thereof while in said boss; and means for directing the flames of combustion outwardly below the preheater.

4. In an oil burner of the character described a hollow preheater adapted to be positioned in a fire box of a stove or the like and provided with an outlet port in the bottom thereof and an inlet port in the top; means for supplying liquid fuel to the burner having one end within the preheater above the outlet port; means for delivering air to the inlet port from outside the fire box; a baffle within the preheater formed to cooperate with the walls of the preheater in directing air from the inlet port to the outlet port through a circuitous path whereby to heat the air; a conductor depending below the end of said liquid fuel supply means and adapted to convey the liquid fuel toward the zone of combustion and the outlet port of the preheater; a tubular boss circumscribing the said conductor and positioned to direct a portion of the air from outside the fire box, downward along the conductor to maintain the temperature of the liquid fuel below the flash point thereof while in said boss; and means for directing the flames of combustion outwardly below the preheater, said conductor being formed to convey the fuel along the exterior surface

thereof, whereby air is caused to impinge upon the liquid fuel from the time it leaves the said end of the supply means and throughout the time of vaporization.

5. In an oil burner of the character described having a combustion chamber, a hollow preheater for supplying air to said chamber provided with an air inlet port and an air outlet port; a conduit for supplying liquid fuel to the burner having one end above the outlet port; a conductor extending from the said end of the conduit into the zone of combustion to conduct liquid by gravity along its exterior surface toward said zone of combustion; a tubular enclosure having an inside diameter greater than the outside diameter of the conductor circumscribing a substantial portion of the length of said conductor to form a space around the latter for the passage of air; and a baffle on the exterior of said tubular enclosure to deflect the remaining portion of the air outwardly therefrom, whereby a small portion of unheated air is passed along said conductor to maintain the liquid fuel thereon below the flash temperature.

25 6. In an oil burner of the character described having a combustion chamber; a hollow preheater for supplying air to said chamber provided with an inlet port and an outlet port; a conduit for supplying liquid fuel to the burner having one end above the outlet port; a conductor extending from the end of said conduit into the zone of combustion to conduct liquid by gravity along its exterior surfaces toward said zone of combustion; a tubular enclosure having an inside 30 diameter greater than the outside diameter of said conductor, said tubular enclosure circumscribing a substantial portion of the length of said conductor to form a space around the latter for the passage of air whereby a small portion 35 of unheated air is passed along said conductor to maintain the liquid fuel thereon below the flash temperature; a baffle on the exterior of said tubular enclosure to direct the remaining portion 40 of the combustion air through a path whereby it is heated.

45 7. In an oil burner of the character described having a combustion chamber; a hollow preheater for supplying air to said chamber provided with an inlet port and an outlet port; a conduit for supplying liquid fuel to the burner having one end above the outlet port; a conductor extending from the end of said conduit into the zone of combustion to conduct liquid by gravity along its exterior surfaces toward said 50 zone of combustion; a tubular enclosure having an inside diameter greater than the outside diameter of said conductor, said tubular enclosure circumscribing a substantial portion of the length of said conductor to form a space around the latter for the passage of air whereby a small portion 55 of unheated air is passed along said conductor to cause air to impinge upon the oil as the same is vaporized; and a baffle on the exterior of said tubular enclosure to direct the remaining portion 60 of the combustion air through a path whereby it is heated.

LE ROY F. DEMING.
